UNITED STATES PATENT OFFICE.

ABRAHAM NEFF CONARD, OF DUNDURN, SASKATCHEWAN, CANADA, ASSIGNOR OF FIFTY-ONE ONE-HUNDREDTHS TO OLE M. NEILSON, GEORGE E. RYSTROM, ERNEST G. HOPPES, JOHN SCHWAGER, DANIEL I. SHULTS, AARON E. HOKANSON, ANDREW OSTERCAMP, FRANK P. LINDBERG, CARL W. EVANS, AND GEORGE T. PETERSON, ALL OF DUNDURN, SASKATCHEWAN, CANADA.

GRAIN-SHOCKER.

1,289,669.

Specification of Letters Patent. Patented Dec. 31, 1918.

Application filed April 11, 1918. Serial No. 227,963.

To all whom it may concern:

Be it known that I, ABRAHAM NEFF CONARD, a citizen of the United States, residing at Dundurn, in the Province of Saskatchewan and Dominion of Canada, have invented a new and useful Grain-Shocker, of which the following is a specification.

The device forming the subject matter of this application is a grain shocker and one object of the invention is to provide a structure of the sort mentioned in which the receptacle which receives the sheaves has a positive movement to and from dumping position. Another object of the invention is to provide novel means for directing the movement of the receptacle. A further object of the invention is to provide novel means for operating the receptacle. The invention aims to improve generally and to enhance the utility of devices of that type to which the invention appertains.

Changes such as a mechanic might make may be resorted to within the scope of what is claimed, without departing from the spirit of the invention.

In the drawings:

Figure 1 shows inside elevation, a device constructed in accordance with the invention; Fig. 2 is top plan; Fig. 3 is an end elevation; Fig. 4 is a perspective showing one part of the automatic clutch release; Fig. 5 is a perspective showing another part of the clutch release; Figs. 6 and 7 are perspectives showing details of the latch mechanism on the doors of the receptacle.

The numeral 1 denotes a main frame adapted to be supported at one side by a reaper and binder (not shown) and supported at the opposite side by a ground wheel 2 carried by an axle 3 mounted in the frame 1 and in an offset bracket 4. An upright auxiliary frame 5 is mounted on the main frame 1. The sides of the frame 1 carry guides 6 having horizontal slots 7 including depending forward ends 8. Arms 9 are pivoted at 10 to the rear end of the frame 1 for vertical swinging movement. A receptacle 11 is located between the arms 9 and is provided with stub shafts 12 on which are journaled grooved rollers 14 working in the slots 7-8 of the guides 6. The receptacle 11 has side bars 15 connected

by a brace 16, the bars being pivoted at 17 to the arms 9.

The receptacle 11 includes a fixed bottom 18 made up of rods or fingers the forward ends of which are free. A rear wall 19 is pivoted at 20 to the sides of the receptacle 11 and to the bottom 18 thereof. There is a bracket 21 on the rear end of the frame 1 to which a longitudinally resilient adjustable connection 22 is pivoted. The connection 22 includes a bar 23 pivoted at 24 to the bracket 21, the forward end of the bar having a socket 25 provided with a slot 26. A bar 27 is pivoted at 28 to the free end of the rear wall 19 and slides in the socket 25, the bar carrying a cross pin 29 having movement in the slot 26 and limiting the relative movement of the parts 23 and 27 under the action of a compression spring 30 which surrounds a portion of the bar 27, one end of the spring abutting against the socket 25, the other end of the spring abutting against a collar 31 held adjustably on the bar 27 by means of a set screw 32 or the like.

Doors 33 are united by hinges 34 with the sides of the receptacle 11 and include springs 35 which tend to swing the doors 33 open. Keepers 36 are carried by the receptacle 11. Guides 37 are mounted on the doors 33 and in the guides, work latches 38 pivoted at 39 to the doors 33, the latches having notches 40 which coöperate with the keepers 36 to hold the doors 33 closed, the latches being actuated by springs 41, attached to the doors, the springs maintaining the latches yieldably engaged with the keepers. Arms 42 are secured to the doors 33 and are adapted to coöperate at their rear ends with standards 43 on the frame 1. The standards 43 include rearwardly inclined lips 44 across which the arms 42 slide, in a way to be described hereinafter, for the purpose of closing the doors 33. Inwardly projecting releasing members 45 are mounted on the sides of the frame 1 and may be adjusted vertically, the releasing members being held in adjusted positions by means of nuts 46 which engage the frame 1. The releasing members 45 coöperate with the latches 38 to disengage the same from the keepers 36 in order to permit

the doors 33 to open responsive to the springs 35.

A pulley 47 is connected to the ground wheel 2 to rotate therewith, and is engaged by a belt 48 coöperating with a pulley 49 on a shaft 50 extended transversely of the frame 1 and journaled thereon. Drums 51 are loose on the shaft 50 but may be connected thereto by clutches 52 operated by levers 53 and 54 fulcrumed on the frame 1, the rear ends of the levers being connected by a link 55, the lever 53 being a hand lever. Flexible elements 56 are connected to the drums 51 and are trained across idlers 57 on the frame 1, the flexible elements being extended upwardly around pulleys 58 on the frame 5 and being connected at 59 with the vertically swinging arms 9.

A sleeve 60 is journaled on the shaft 50 but may be connected thereto by a clutch 61 controlled by a lever 62 fulcrumed on the rear end of the frame 1. The sleeve 61 carries drums 63 about which are engaged flexible elements 64 secured to the stub shafts 12 on the receptacle 11.

One of the vertically swinging arms 9 has an extension 65 projecting rearwardly beyond the pivotal mounting 10 of the said arm, the extension being prolonged laterally as shown in Fig. 4, the part 66 carrying a cam 67 which coats with the clutch lever 53. A rock shaft 68 is journaled on the rear end of the frame 1 and includes a finger 70 which overhangs the bar 23 of the connection 22 which unites the pivoted wall 19 of the receptacle 11 with the bracket 21 on the frame 1. The outer end of the rock shaft 68 has an arm 71 terminating in a transverse cam 72 coating with the clutch lever 62.

Let it be supposed that the receptacle is in a position to receive the sheaves of grain from the binder. Then the parts are arranged as shown in solid line in Fig. 1. The doors 33 are disposed at the bottom of the receptacle 11 and are held closed because the latches 38 on the doors are engaged with the keepers 36 on the receptacle. The part 18 of the receptacle 11 is disposed vertically and the swinging wall 19 of the receptacle 50 is held in an open position by the connection 22, the rollers 14 on the receptacle being disposed at the rear ends of the horizontal slots 7 in the guides 6, the arms 9 being swung downwardly into approximately parallel relation to the sides of the frame 1. The sheaves of grain are now delivered in any desired number into the receptacle 11 and collect on the closed doors 33.

When a shock of sufficient size has accumulated in the receptacle 11, the lever 53 is manipulated to connect the drums 51 with the shaft 50 by way of the clutches 52. The shaft 50 is driven from the ground wheel 2 by the pulley 47, the belt 48 and the pulley 49. The flexible elements 56 are reeled on

the drums 51 and, passing over the pulleys 57 and 58, elevate the forward ends of the arms 9, the wall 19 being closed against the shock in the receptacle 11 by the action of the pivoted connection 22, it being noted that, owing to the presence of the spring 30, a yieldable pressure on the shock is afforded. When the arms 9 are swung upwardly, the forward end of the receptacle 11 is raised because the bars 15 on the receptacle are pivoted at 17 to the arms, the rollers 14 on the receptacle moving forwardly in the horizontal slots 7 of the guides 6 on the frame 1. Ultimately, the rollers 14 on the receptacle move downwardly in the depending ends 8 of the guide slots, the receptacle 11 being in a vertical position, the wall 19 being vertically disposed and the bottom 18 being horizontally disposed, the butt of the shock coming into contact with the ground, between the rods or fingers which make up the bottom. Just about the time that the butt of the shock comes into contact with the ground, the latches 38 engage the releasing members 45, the latches being disengaged from the keepers 36, whereupon the doors 33 fly open under the action of the springs 35. As the structure moves forwardly, the shock, which is now in an upright position, passes off the bottom 18 of the receptacle 11 and out between the open doors 33, the shock being left standing upright on the ground.

The operator now manipulates the lever 62 and couples the sleeve 60 and the drums 63 with the shaft 50, the flexible elements 64 being drawn rearwardly to cause the rollers 14 on the receptacle first to rise in the depending ends 8 of the guide slots and then to move rearwardly in the horizontal parts 7 of the slots. During this operation, the arms 9 first swing upwardly and then downwardly into parallel relation to the sides of the frame 1, the wall 19 of the receptacle 11 being swung to an open position by the connection 22, as shown in Fig. 1. When the rollers 14 on the receptacle 11 pass into the horizontal parts 7 of the guide slots, the rear ends of the arms 42 on the doors 33 engage the standards 43 and slide downwardly along the forward surfaces thereof, the arms passing rearwardly across the inclined lips 44 of the standards. The engagement between the arms 42 and the standards 43 closes the doors 33 and when the doors arrive at a closed position, the latches 38, under the action of the springs 41, engage in their notched portions 40 with the keepers 36, to hold the doors closed. The parts are now restored to the position of Fig. 1 and the receptacle 11 is so placed as to receive the sheaves of another shock. It has been pointed out hereinbefore that the lever 53 is manipulated to swing the arms 9 upwardly and to dispose the recep-

tacle 11 in a vertical position at the time the shock passes out of the receptacle. When the rollers 14 move downwardly in the parts 8 of the guide slots, it is desirable that the 5 flexible elements 56 be permitted to pay out with a run, and in order that this may be done, the clutches 52 are disengaged automatically from the drums 51 as follows: When the forward ends of the arms 9 swing 10 upwardly, the extension 65 and the cam 67 on one arm (Fig. 4) move downwardly, the cam 67 operating the lever 53 so that the drums 51 no longer are connected with the shaft 50 by the clutches 52. Likewise, it is 15 desirable that the flexible elements 64 be released at an appropriate time as the receptacle swings downwardly into the receiving position of Fig. 1. It is for this purpose that the rock shaft 68 is provided. When 20 the connection 22 swings upwardly, the bar 23 thereof engages the finger 70 and rocks the shaft 68 by means of the arm 69, the arm 71 causing the cam 72 to shift the lever 62 thereby retracting the clutch 61 and setting the sleeve 60 and its drums 63 free from the shaft 50.

I claim:—

1. A grain shocker comprising a frame; a guide thereon; an arm mounted to swing 30 on the frame; a receptacle pivoted to the arm and including a part slideable in the guide; means connected with the arm for operating the arm to cause said part to slide in one direction in the guide and to move the receptacle to dumping position; means assembled with the receptacle for causing said part to slide in an opposite direction in the guide and to move the receptacle into receiving position; a door pivoted to the 35 receptacle; a latch movable on the door; a keeper on the receptacle wherewith the latch engages to hold the door closed; a releasing member on the frame and coöperating with the latch to disengage the latch from the keeper when the receptacle moves to dumping position; and frame-carried means coöperating with the door to close the door when the receptacle moves to receiving position.
2. A grain shocker comprising a frame; a guide thereon; an arm having its rear end pivoted to the frame; a receptacle pivoted to the arm intermediate the ends of the arm and including a part slideable in the guide; 40 a flexible element connected with the forward end of the arm for raising the arm to cause said part to slide in one direction in the guide and to move the receptacle to dumping position; a flexible element assembled with the receptacle for causing said part to slide in an opposite direction in the guide and to move the receptacle into receiving position; a driven member on the rear end of the frame; means for coupling 45 the flexible elements selectively to the

driven member; and means for guiding the first-specified flexible element upwardly from the arm, downwardly, and rearwardly to the corresponding part of said coupling means.

3. A grain shocker comprising a frame; an arm pivoted to the frame; a receptacle pivoted to the arm; means on the frame for guiding the receptacle to and from dumping position; a wall pivoted to the receptacle; and a longitudinally-resilient thrust connection extended rearwardly from the wall, the forward end of the connection being pivoted directly to the wall, and the rear end of the connection being pivotally assembled with the frame against longitudinal movement.

4. A grain shocker comprising a frame; a guide thereon and including an approximately horizontal portion and a depending portion; an arm pivoted to the frame; a receptacle pivoted to the arm and having a part adapted to traverse the horizontal portion of the guide and to move into the depending portion thereof when the receptacle 85 assumes a dumping position; means assembled with the arm for moving the arm to cause the receptacle to assume dumping position; and means assembled with the receptacle for retracting said part of the receptacle in the guide and restoring the receptacle to receiving position.

5. A grain shocker constructed as set forth in claim 4 and further characterized by the provision of a door pivoted to the receptacle; a latch movable on the door; a keeper on the receptacle wherewith the latch engages to hold the door closed; a releasing member on the frame and coöperating with the latch to disengage the latch from the keeper when the receptacle moves to dumping position; and frame-carried means coöperating with the door to close the door when the receptacle moves to receiving position.

6. A grain shocker constructed as set forth in claim 4 and further characterized by the provision of a wall pivoted to the receptacle; and a longitudinally resilient thrust connection pivoted to the wall and the frame.

7. A grain shocker constructed as set forth in claim 4 and further characterized by the provision of a door pivoted to the receptacle; a latch movable on the door; a keeper on the receptacle wherewith the latch engages to hold the door closed; a releasing member on the frame and coöperating with the latch to disengage the latch from the keeper when the receptacle moves to dumping position; frame-carried means coöperating with the door to close the door when the receptacle moves to receiving position; a wall pivoted to the receptacle; and a longitudinally resilient thrust connection pivoted to the wall and the frame.

8. A grain shocker constructed as set forth

in claim 4 and further characterized by the provision of mechanism coacting with the arm-moving means for releasing the same automatically when said part of the receptacle moves into the depending portion of the guide.

9. A grain shucker constructed as set forth in claim 4 and further characterized by the provision of mechanism coacting with the means assembled with the receptacle, for releasing said means when said part of the receptacle moves into the approximately horizontal portion of the guide from the depending portion of the guide.

10. 10. A grain shucker constructed as set forth in claim 4 and further characterized by the provision of mechanism coacting with the

arm-moving means for releasing the same automatically when said part of the receptacle moves into the depending portion of the guide; and mechanism coacting with the means assembled with the receptacle, for releasing said means when said part of the receptacle moves into the approximately horizontal portion of the guide from the depending portion of the guide.

In testimony that I claim the foregoing as my own, I have hereto affixed my signature in the presence of two witnesses.

ABRAHAM NEFF CONARD.
